UNITED STATES PATENT OFFICE

134,160

DESIGN FOR A REFRIGERATOR

Howard B. Barber, Glenview, Ill., assignor to Montgomery Ward & Co., Incorporated, Chicago, Ill., a corporation of Illinois

Application October 22, 1941, Serial No. 103,862

Term of patent 7 years

To all whom it may concern:

Be it known that I, Howard B. Barber, residing at Glenview, in the county of Cook and State of Illinois, have invented a new, original, and ornamental Design for a Refrigerator, of which the following is a specification, reference being had to the accompanying drawing, forming a part thereof.

In the drawing:

erator, showing my new design;

Figure 2 is a side elevational view; and
Figure 3 is a perspective view thereof.
The characteristic features of my new design reside in the portions shown in solid lines.

I claim:

The ornamental design for a refrigerator, substantially as shown and described.

HOWARD B. BARBER.
